DESIGN FOR A GLIDER

Carl H. Oermann, York, Pa.

Application March 6, 1940, Serial No. 90,716

Term of patent 7 years

To all whom it may concern:

Be it known that I, Carl H. Oermann, a citizen of the United States of America, residing at York, in the county of York and State of Pennsylvania, have invented a new, original, and ornamental Design for a Glider, of which the following is a specification, reference being had to the accompanying drawings, forming part thereof, wherein

Fig. 1 is a perspective view of a glider embodying my new design;

Fig. 2 is an end elevational view of the same on an enlarged scale; and

Fig. 3 is a plan view of one of the arms thereof.

I claim:

The ornamental design for a glider, as shown.

CARL H. OERMANN.
